BLADE MAGAZINE

Billi Bowen, New York, and John Wark, Bronx, N. Y., assignors to Gillette Safety Razor Company, Boston, Mass., a corporation of Delaware

Continuation of design application Serial No. 140,376, July 18, 1947. This application June 2, 1949, Serial No. 3,016

Term of patent 14 years

(Cl. D22—3)

To all whom it may concern:

Be it known that we, Billi Bowen and John Wark, both citizens of the United States, residing at 5 West 65th Street, New York, N. Y., and 1051 University Avenue, Bronx, New York respectively, have invented a new, original, and ornamental Design for Blade Magazines, of which the following is a specification, reference being had to the accompanying drawings, forming part thereof.

This application is a continuation of our application D. 140,376 filed July 18, 1947, now abandoned.

In the drawings:

Fig. 1 is a view in perspective of a blade magazine, showing our new design;

Fig. 2 is a view in side elevation.

Fig. 3 is view of the magazine as seen from the left end; and

Fig. 4 is a view of the magazine as seen from the right end.

We claim:

The ornamental design for a blade magazine, as shown.

BILLI BOWEN.
JOHN WARK.
